UNITED STATES PATENT OFFICE.

ALEXANDER A. HUDSON, OF CINCINNATI, OHIO.

HEEL-BUILDING MACHINE.

1,176,831.

Specification of Letters Patent. Patented Mar. 28, 1916.

Application filed August 13, 1915. Serial No. 45,398.

To all whom it may concern:

Be it known that I, ALEXANDER A. HUDSON, a citizen of the United States of America, and resident of Cincinnati, county of 5 Hamilton, State of Ohio, have invented certain new and useful Improvements in Heel-Building Machines, of which the following is a specification.

This invention relates to improvements in 10 heel building machines and particularly to heel building machines of the type disclosed in my United States Letters Patent Number 1,156,842.

An object of my present invention is to 15 produce means for quickly and uniformly adjusting the clamps mounted on the rotatable clamp support to receive heel blocks of different sizes.

A further object is to produce means for 20 adjusting the clamp jaws predetermined amounts to receive rough heel blocks of certain sizes.

These and other objects are attained in the device described in the following specification and illustrated in the accompanying drawings in which:

Figure 1 is a side elevation of a heel building machine having a clamp setting device embodying my invention coöperating therewith. Fig. 2 is a fragmental elevation showing my clamp setting device coöperating with the clamps mounted on the rotatable clamp support. Fig. 3 is a diagrammatic view illustrating the operation of the clamp setting device embodying my invention.

The heel building machine disclosed in my above mentioned patent and illustrated in coöperation with the clamp setting device constituting the novel subject matter of my 40 present application, comprises a frame 4, a blank assembling device 5, a rotatable clamp support 6, and a series of clamps 7 mounted on the clamp support. Adjacent to the clamp support and surrounding the blank assembling device 5, is a table 8 having thereon a series of bins 9 for the various sizes of heel blanks used in the construction of heel blocks.

Adjacent to the back of the table, and secured to a board 10 covering the bins, is the clamp setting device embodying my invention. This device comprises a frame 11 having a series of pins 12 reciprocally mounted in holes extending transversely 55 thereof. The outer ends of these pins are provided with knobs 13 by means of which

the pins may be reciprocated to move their inner ends toward or away from the periphery of the rotatable clamp support. Each of the clamps mounted on the clamp support, is provided with two relatively movable jaws 14 and 15, the jaw 14 being operatively connected with the clamp operating handle 16, with the jaw 15 adjustably mounted to be moved toward or away from the jaw 14, by means of an adjustment screw 17 passing through a lug 18 formed on the base 19 of the clamp, and engaging the rear face of the jaw. In the projecting end of the screw threaded shaft are two pins 20 and 21 mounted in bores located at right angles to one another. The clamp setting device is located on the board 10 in such a position that its pins 13 will be engaged by the ends of the pins 20 and 21 in the adjustment screw of each of the clamps as the clamp support 6 is rotated, as shown in Fig. 3. This causes rotation of the adjustment screw of each clamp through a quarter of a revolution thereof, each time one of the pins 13 of the clamp setting device is passed. The action of the coöperating pins 13, 20 and 21 is therefore like that of a rack and pinion in which the rack imparts rotary motion to the pinion as it passes over it. The amount of rotation imparted to the adjustment screw is governed by the number of pins 13 which have been moved to engage the pins 20 and 21, so that the effect produced is that of increasing or decreasing the length of the rack over which the pinion comprising the screw threaded shaft and its pins 20 and 21, moves.

In the machine embodying my invention, the screw 17 is provided with screw threads having a certain number of threads per inch, as for example 16, so that for each engagement of the pins 20 or 21 with each pin 13 the screw will be rotated through one quarter of a revolution and the jaw 15 will be moved inwardly or outwardly as desired, for a distance of $1/64$ of an inch, according to the direction of movement of the clamp support 6. The distance of adjustment of the jaw 15 each time it passes the clamp setting device, will therefore depend upon the number of pins 13 which have been moved into the path of movement of the pins 20 and 21. In Fig. 2 of the drawings, three of the pins 13 have been moved to be engaged by the pins 20 and 21, so that the amount of adjustment afforded by

this arrangement, with 16 screw threads per inch as in the above example, would give an adjustment of $3/64$ of an inch of the jaw 15. In order to adjust the jaw 15 toward the jaw 14 counter clockwise rotation of the support 6, as viewed in Fig. 1, would be necessary, while to adjust the jaw in an opposite direction, clockwise rotation thereof is necessary.

10 I contemplate employing any coöperating rack and pinion construction in which the rack is provided with removable teeth, as shown in the drawings illustrating an embodiment of my invention.

15 Having thus described my invention, what I claim is:

1. In a heel building machine the combination of a movable clamp support, a series of clamps mounted on the clamp support, 20 and a single clamp setting means located adjacent to the support, to be engaged by the clamps when the support is moved, whereby the clamp jaws will be uniformly adjusted to receive heel blocks between them, said means being removable from engagement with the clamps to permit unobstructed movement of the support after the clamps are adjusted.

2. A heel building machine comprising a 30 movable clamp support, a series of clamps mounted on the clamp support, and adjustable means located adjacent to the support, to be engaged by the clamps when the support is moved whereby the clamp jaws will be uniformly adjusted predetermined distances apart when the clamps are released, said means being removable from engagement with the clamps to permit complete and unobstructed movement of the support 40 after the clamps are adjusted.

3. In combination in a heel building machine, a series of clamps, a vertically rotatable wheel adapted to mount the clamps on its rim and a clamp setting device mounted adjacent to the wheel and consisting of 45

a rack having movable means for increasing or decreasing its length, each of said clamps having an adjustable jaw, and means for adjusting said jaw, said means being located adjacent to the clamp setting device and 50 having a toothed end adapted to engage the rack, whereby the jaw will be moved to adjusted positions when the wheel is rotated to bring the teeth and rack into and out of engagement with one another.

4. In a heel building machine, a series of clamps, a rotatable clamp support for mounting the clamps and a clamp setting device located adjacent to the clamps, each of said clamps consisting of an adjustable 60 jaw, a clamping jaw, and means for adjusting the adjustable jaw, comprising an adjustment screw operatively connected with said adjustable jaw and a series of pins located in the end of the adjustment screw 65 to form a toothed pinion, said clamp setting device consisting of a series of movable pins forming a rack adapted to be engaged by the pins of the adjacent screw to rotate the screw.

5. A heel building machine comprising a movable clamp support, a series of clamps mounted on the clamp support, having a clamp jaw and an adjustable jaw, and a means located adjacent to the support and adapted 75 to be rotatively connected with the adjustable jaw of each clamp when the support is rotated, to adjust the adjustable jaws, said means being adjustable to adjust the jaws various desired amounts, and removable 80 from operative connection with the adjustable jaws to permit the complete and unobstructed movement of the support.

In testimony whereof, I have hereunto subscribed my name this tenth day of August, 1915.

ALEXANDER A. HUDSON.
